(57) **CLAIM**

I claim, the ornamental design for a car, including toy-car, motor car, replica car and scale model car, as shown and described.

DESCRIPTION

FIG. 1 is a front elevation view of a car, including toy-car, motor car, replica car and scale model car, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a front left side perspective view thereof; and,

FIG. 7 is a rear right side perspective view thereof.

The broken lines shown in the drawings illustrate portions of the car, including toy-car, motor car, replica car, and scale model car that form no part of the claimed design.
